UNITED STATES PATENT OFFICE.

FRANCIS J. COATES, OF CINCINNATI, OHIO.

DESIGN FOR A FOOTSTOOL FOR BARBERS' CHAIRS.

Specification forming part of Design No. 6,725, dated June 24, 1873; application filed June 14, 1873.

To all whom it may concern:

Be it known that I, FRANCIS J. COATES, of Cincinnati, in the county of Hamilton and State of Ohio, have invented a new and original Design for a Footstool for Barbers' Chairs, of which the following is a specification:

The accompanying photographic illustration fully represents my design, which consists of the standards A and the supports for the lower principal step B, contrived in the form of a serpent, as represented. It also consists of the covering-plates of the lower and upper steps having perforations, and also having my name formed on them.

I claim as my invention—

1. The design for the standards and the lower step supports, substantially as set forth.
2. The design for the step-cover plates, substantially as set forth.

FRANCIS J. COATES.
